UNITED STATES PATENT OFFICE.

BERRY A. BROWN, OF FRANKLIN, OHIO.

ENVELOP.

SPECIFICATION forming part of Letters Patent No. 651,456, dated June 12, 1900.

Application filed October 20, 1899. Serial No. 734,232. (No model.)

To all whom it may concern:

Be it known that I, BERRY A. BROWN, a citizen of the United States, residing at Franklin, in the county of Warren and State of Ohio, have invented certain new and useful Improvements in Envelops, of which the following is a specification, reference being had therein to the accompanying drawings.

My present invention relates to a novel envelop; but before proceeding with a description thereof it may be well, by way of premise, to call attention to the considerations which have governed the production of this device.

15 It is a fact well understood that first-class mailing-packets or envelopes—that is to say, those which are sealed by simply turning down a gummed sealing-flap—are filled and sealed with much greater facility and despatch than any other form. The reason for this is that after the contents have been inserted the sealing is effected by a single movement of the hand, simultaneously turning down the flap and causing it to adhere to the body of the envelop. A further reason is that a great many machines have been produced for filling and sealing such packets. It is equally well known that second-class mail-matter must be unsealed in the technical sense to permit inspection of the contents. My efforts, therefore, have been directed to the production of an envelop which may be closed and secured by the manipulation necessary for sealing first-class matter, but which when so closed 30 will be secured by such detachable means as will bring the packet under the head of second-class matter.

To the accomplishment of this end the invention consists in the production of an envelop having a separate sealing-tongue detachably retained by the body of the envelop and to which the sealing-flap is designed to be sealed in the ordinary manner.

Referring to the drawings, Figure 1 is a 45 perspective view of my envelop in the open position. Fig. 2 is a similar view thereof closed, and Fig. 3 is a detailed view of the tongue detached.

Referring to the numerals of reference indicating like parts in the several views, 1 indicates an envelop, which may be of ordinary form, comprising a body portion or retainer

2 and a sealing-flap 3, adapted to be turned down over the opened edge of the retainer and having gum or other adhesive sealing material 4 along a portion of the edge of its under side.

To the flap side of the envelop (as distinguished from its front or address side) is detachably retained a separate sealing-tongue 6c 5, the retention of which is effected by means which if employed for the retention of the sealing-flap would constitute a second-class seal under the postal laws.

In use the envelop is filled and the sealing-flap is turned down and sealed, as usual; but instead of being sealed to the envelop it is sealed to the upper end of the separate tongue 5, the retaining means of which now constitutes a second-class seal for the envelop. 70

There is another aspect in which my invention may be viewed. A certain class of retainers, which have come to be known as "safety-envelops," are sealed or secured by means which is designed when tampered with 75 to leave some evidence of the surreptitious entry. These safety-seals, while effective for the purpose mentioned, are in many cases difficult to manipulate, and their use in connection with filling, sealing, and addressing 80 machines is impossible. My invention is therefore further directed to such adaptation of the envelop as will permit the safety-seals to be closed during the manufacture of the envelop, which may then be filled, sealed, 85 and addressed by the ordinary forms of such machines and which when delivered from the machine will be safety-sealed second-class matter.

In the drawings I have illustrated for example one form of safety second-class sealing, which consists in providing three or more parallel slits 6, 7, and 8, defining fragile straps 9 and 10. The lower end of the separate detached tongue is passed through the 95 slit 6, under both straps, out through the bottom slit 8, over the strap 10, and under the strap 9, and is thus detachably retained by the body of the envelop. The envelop thus constructed is delivered by the manufacturer, 100 and the user is enabled to fill and seal them as ordinary first-class matter, while having the advantages accruing from safety-sealed second-class matter. I wish it understood,

however, that I do not limit myself to the structural details defined, as any form of tongue or tongue-retaining means may be employed and as many minor changes might 5 be effected—such, for instance, as the provision of adhesive material upon the upper end of the tongue exclusively to prevent the possibility of the adhesion of any portion of the sealing-flap to the envelop.

10 Therefore what I claim, and desire to secure by Letters Patent, is—

An envelop having a sealing-flap, a separate sealing-tongue detachably retained by the envelop and means for effecting a permanent connection between the sealing flap and tongue when the former is turned down. 15

In testimony whereof I affix my signature in presence of two witnesses.

BERRY A. BROWN.
